United States Patent Office

Des. 201,773
Patented July 27, 1965

201,773

RECOVERABLE SINGLE STAGE SPACECRAFT BOOSTER

James E. Webb, Administrator of the National Aero-nautics and Space Administration, with respect to an invention of Philip Bono

Filed June 16, 1964, Ser. No. 80,421

Term of patent 14 years

(Cl. D71—1)

FIG. 3

FIG. 4

FIG. 2

FIGURE 1 is a perspective view of a recoverable single stage spacecraft booster showing my new design;

FIGURE 2 is a side elevational view thereof on a reduced scale;

FIGURE 3 is a top plan view thereof; and

FIGURE 4 is a rear view thereof.

What is claimed is:

The ornamental design for a recoverable single stage spacecraft booster, substantially as shown and described.
